METHOD AND APPARATUS FOR ASSEMBLING WRAPPED BOXES

Herman A. Carruth, Northford, Conn., assignor to National Folding Box Company, New Haven, Conn., a corporation of New Jersey

Application May 25, 1938, Serial No. 209,920

20 Claims. (Cl. 93—40)

This invention relates to a method and apparatus for assembling wrapped boxes, and more particularly to an improved method and apparatus whereby paperboard boxes comprising a rigid body structure to which is affixed a covering wrapper, may be manufactured and assembled automatically at a high production rate at relatively low cost.

In accordance with my invention, an improved method of assembling set-up wrapped boxes is provided comprising a series of assembly steps which can be automatically performed in rapid succession so as to produce a rigid and highly serviceable and desirable wrapped box which can be manufactured and sold at a price comparable to unwrapped boxes.

In the packaging of hosiery, wearing apparel and other articles of merchandise, a strong and rigid box is desired for the reason that such boxes must be piled in relatively high stacks during shipment and storage and during residence on the merchant's shelves. Due to the weight of the superimposed boxes the lowermost boxes in the stack are subject to severe crushing strains which often cause the box bottoms or covers to buckle, side and end walls to flare outwardly, and the boxes to tear or split at the corners. My improved method and apparatus is directed to the provision of a highly serviceable wrapped box which will withstand and hold up under severe compression strains and will maintain its shape and form and fully protect the merchandise packed therein when subjected to the most severe use and abuse. My improved method and apparatus is designed to assemble a prepared wrapper blank onto a prepared body blank which possesses a high degree of stiffness and strength, and thereafter to apply adhesive to the predetermined areas of the body blank, to properly align and register the wrapper blank on the body blank, to stretch the wrapper blank, to apply adhesive to defined areas of the wrapper blank, to fold the side and end wall sections and the corner tabs into box-assembled position, and, finally, to complete the application of the wrapper blank to the box body. The mechanism provided for the purpose requires little personal supervision once placed in operation, and the successive assembly steps are performed in synchronized relation in rapid succession. The prepared body blanks and wrapper blanks are fed into the apparatus adjacent one end thereof and the finished wrapped box is ejected at the other end thereof completely and fully assembled and ready to receive merchandise.

55 The apparatus is so constructed that certain

defined assembling operations can be conveniently performed at the box-assembling plant and the assembled unitary wrapper and body blanks may then be shipped in flat extended position to the user or merchandise packer, who can conveniently employ another section of the apparatus to complete the final assembly and erection of the wrapped box as the boxes are needed. Substantial savings in shipping and storage costs can thus be realized. If shipping and storage costs are not 10 a serious problem, the entire assembly and box-erecting operation can be performed in the plant of the box manufacturer or the plant of the user from a supply of prepared body and wrapper blanks.

An object of this invention is to provide an improved method of assembling wrapped boxes which permits of high speed, economical production.

Another object of this invention is to provide an improved method of assembling boxes from a prepared relatively stiff body blank and a prepared relatively bendable wrapper blank in a series of steps which can be economically and speedily performed by automatic machinery.

Another object of this invention is to provide an improved apparatus for assembling wrapped boxes.

Another object of this invention is to provide an improved apparatus adapted to feed, glue and assemble a prepared relatively stiff body blank and a prepared relatively flexible wrapper blank into a rigid highly serviceable wrapped box at a production rate substantially greater than heretofore obtainable by box-wrapping apparatus heretofore known and employed.

Other objects of this invention will become apparent as the disclosure proceeds.

Various other features and advantages of the invention will be apparent from the following 40 particular description and from an inspection of the accompanying drawings.

Although the novel features which are believed to be characteristic of this invention will be particularly pointed out in the claims appended 45 hereto, the invention itself, as to its objects and advantages, and the manner in which it may be carried out, may be better understood by referring to the following description taken in connection with the accompanying drawings forming 50 a part thereof, in which

15 Fig. 23 is a fragmentary perspective view of a portion of the blank conveyor which moves the blank generally at right angles to the conveyor illustrated in Figs. 6 and 7, Fig. 23 illustrating particularly the manner in which the assembled 20 blanks are engaged by the conveyor belts, further illustrated in Figs. 8 and 9;

25 Fig. 24 is a perspective view of the rollers which fold the end walls of the wrapper blank and body blank at an angle to the bottom section thereof, a step performed by that section of the machine illustrated in Figs. 10 and 11;

30 Fig. 25 is a perspective view of the rocker arms which operate to fold the corner tabs of the wrapper blank and body blank generally at right angles to the bottom section thereof, an operation performed by the section of the machine illustrated in Figs. 10 and 11;

35 Fig. 26 is a perspective view of the corner tab guides which operate to retain the corner tabs of the wrapper blank and body blank assembly generally at right angles to the bottom section thereof while the glue rollers operate to apply adhesive to the end flaps of the wrapper blank, an operation performed by the section of the 40 machine illustrated in Figs. 10 and 11;

45 Fig. 27 is a fragmentary perspective view of the folding elements which operate to fold the side walls and end walls of the body and wrapper assembly into box-forming position, which elements are more fully illustrated in Figs. 12 to 15 inclusive;

50 Fig. 28 is a perspective view of the body and wrapper assembly showing the corner tabs folded at right angles to the bottom section as the initial 55 step in erecting the box, a step performed by the machine elements illustrated in Figs. 12 to 15 inclusive;

Fig. 29 is a perspective view of the body and wrapper assembly wherein the corner tabs have been folded inwardly and the side walls are in the process of being turned at right angles to the bottom section, a step performed by the machine elements illustrated in Figs. 12 to 15 inclusive;

60 Fig. 30 is a perspective view of the box and wrapper assembly showing the end walls raised into box-forming position, a step performed by the machine elements illustrated in Figs. 12 to 15 inclusive;

65 Fig. 31 is a perspective view of the box and wrapper assembly showing the end wall flaps of the wrapper blank about to be turned inwardly into adhesive contact with the inside face of the end wall of the body, a step performed by the machine elements illustrated in Figs. 12 to 15 70 inclusive; and

75 Fig. 32 is a perspective view of the completed box as it appears assembled by the method and apparatus herein disclosed.

Similar reference characters refer to similar 75

parts throughout the several views of the drawings and the specification.

In the manufacture of wrapped boxes by the method and apparatus comprising this invention, body-forming blanks A, which may be of the general type illustrated in Fig. 1, are first prepared. The body-forming blanks may be formed of relatively strong paperboard of the necessary strength and stiffness to properly support and retain the merchandise in the box. The blank is generally of rectangular form, comprising a bottom section a of rectangular shape, side wall sections b hinged to the bottom section a by suitable score lines, and end sections c also hinged to the bottom section a by suitable score lines. A corner tab d is hinged to each end of the side wall sections b which, when the box is erected, are folded to lie adjacent the inside face of the end wall sections c. As illustrated in Fig. 1, each corner tab or stay d is separated from the ends of the side wall sections c by a cut line e. The bottom section a is coated with a layer of adhesive x during the assembly operation. The body blanks A may be cut and scored from large sheets or rolls of suitable paperboard on an automatic cutting and scoring machine at a high production rate.

It has heretofore been customary to first completely assemble the box body from a blank A, as shown in Fig. 1, by erecting the sides and end walls and staying the corners before the wrapper is applied. In accordance with my invention, the wrapper blank is attached and secured to the body blank before erection of the body blank, and the side and end walls of both the body and wrapper blanks are erected as a unit. As shown more particularly in Fig. 2, the wrapper blank B comprises a bottom section a' which is of such size as to neatly cover the outside face of the bottom section a of the body blank; side wall sections b' of such size as to extend over the outside face of the side wall sections b of the body blank; end wall sections c' of such size as to extend over the outside face of the end wall sections c of the body blank, and corner tabs d' of such size as to extend over the corner tabs d of the body blank. A side wall flap b'' extends from each side wall section b' of the wrapper blank and are each coated during the assembly operation with a strip of adhesive y. During the assembly operation these flaps are folded and pressed into adhesive contact with the inside face of the side wall sections b of the body member. After the body corner tabs d and wrapper corner tabs d' have been folded inwardly, the end wall flaps c'' extending from the end wall sections c' of the wrapper blank are coated with a strip of adhesive z during the assembly operation and these flaps are then folded into adhesive contact with the inside face of the end wall sections c of the body blank.

The wrapper blank may comprise a sheet of paper which may be suitably decorated or treated to give the desired finished appearance to the box. The wrapper blanks may be cut and scored from large sheets or rolls of selected paper or paper-board on an automatic cutting and scoring machine at a high speed production rate. The wrapper blank may be formed of relatively tough, strong sheet material as to appreciably add to the stiffness and strength of the box. The term "wrapper" or "wrapper blank" as hereinafter used is to be understood to cover wrappers of any quality of tough paper or finished cardboard which has the desired bending and wrapping qualities. The method and apparatus comprising this invention is designed to wrap and assemble boxes of any

size or depth, and the machine itself may be provided with adjustable or interchangeable operating elements whereby boxes of different size may be assembled thereon.

The box-assembling machine comprises a series of operating mechanisms each designed to perform defined operations upon the blank, which may be generally referred to as, the body and wrapper feeding mechanism, the side wall gluing and wrapping mechanism, the side wall stretching mechanism, the end wall bending mechanism, the end wall gluing mechanism, and the box-assembling mechanism. For convenience in description each of the separate mechanisms above referred to will be separately described and discussed.

Body and wrapper feeding mechanism

Referring more particularly to Figs. 3, 4 and 5, the body blanks A, which have been cut and scored as illustrated in Fig. 1, are placed in a suitable hopper having an inclined rear wall 2 and retaining side walls 3, the hopper being supported upon a suitable framework 1 a convenient distance above the floor. A body blank feed roller 4 mounted upon a shaft 5 suitably journaled in the framework 1, is provided with rubber blank-engaging buttons or projections 6 or other blank-engaging means which operate to feed a single body blank A onto a belt conveyor 11 at each revolution of the feed roller 4. The feed roller is fixed to a shaft 5 rotatably mounted in suitable bearings provided in the framework 1 and is positively driven by a driving gear 7 fixed to one end of the shaft 5. The driving gear 7 meshes with a driving gear 8 fixed to shaft 20 rotatably mounted in the framework 1. The shaft 20 may be provided with a pulley wheel 10 or other means which is operatively connected to a driving motor or other power source.

The belt 11 may be made of woven fabric and is of such width as to conveniently support the blanks, means being provided for positively advancing the belt 11. A belt-supporting roller 16 is fixed to the drive shaft 20 which is positioned at the head of the apparatus. The belt is trained over a supporting roller 17 fixed to a shaft 21 rotatably mounted in the framework 1 spaced from the roller 16 so that the upper run of the belt presents a table-like surface advancing forwardly. The shaft 20 upon which the roller 16 is mounted is driven by the guide pulley wheel 10 in the manner heretofore described.

Thus it is seen that as the feed roller 4 revolves the abutments 6 operate to engage one of the body blanks A and deposit it on the upper advancing run of the belt 11 until the abutments 6 release the blank. It will be appreciated that the diameter of the feed roller 4 is somewhat greater than the length of the body blank so that the body blanks are fed onto the belt 11 at spaced intervals and a single body blank is fed onto the table with each revolution of the feed roller 4, which is rendered possible by the fact that the feed roller 4 and the belt supporting roller 20 are driven in synchronism from the pulley wheel 10.

The top face of the bottom section a of the body blank A, which is the outside face of the box body when assembled, is coated with adhesive x, adhesive-applying means being provided to fully coat the entire area of the bottom section a without applying adhesive to the side wall sections b or the end wall sections c of the body blank. The adhesive-applying mechanism, as illustrated more particularly in Figs. 3, 4, 5 and 75

16, comprises a glue roller 25 fixed to a shaft 26 rotatably mounted in suitable bearings provided in the framework 1. The shaft 26 may be provided with a sprocket wheel 27 over which is trained a drive chain 28, which drive chain is trained over a sprocket wheel 29 fixed to the driven shaft 5. The cylindrical surface of the glue roller 25 is coated with adhesive by a suitable applicator roll 30 which is mounted to freely roll in contact with the periphery of the glue roller 25. A suitable glue pot 31 supplies the adhesive to the applicator roll 30 through the glue outlet 32 therein. Suitable means may be provided to maintain the glue in the glue pot 31 at the proper liquid temperature.

15 It will be noted by referring more particularly to Figs. 4, 5 and 16 that the glue roller 25 is provided with a depression 29 in the surface thereof into which no glue is applied. The width 20 of the channel 29 is such that when the glue roller 25 rotates, no adhesive will be applied to the end wall sections c of the body blank or to the belt 11 between successive advancing body blanks. The glue-applying periphery of the glue 25 roller 25 corresponds to the length of the bottom section a of the body blank so that the adhesive is applied to the top surface of the bottom section a only.

30 The wrapper blanks B which have been cut to the required shape, as illustrated in Fig. 2, are placed in a suitable feed hopper immediately ahead of the glue roller 25, the feed hopper comprising an inclined rear wall 35 and side wall 36. The successive wrapper blanks are drawn from the hopper by means of a feed roller 37 affixed to a shaft 38 rotatably mounted in the framework 1 of the machine. A drive sprocket 40 is connected to one end of the shaft 38 and is driven from a drive sprocket 42 fixed to the shaft 5 by means of a drive chain 41 trained over the sprockets 40 and 42. Blank-engaging buttons 39 are provided on the periphery of the feed roller 37 which operate to engage the topmost wrapper blank B in the hopper at each successive revolution of the feed roller 37. The feed roller 37 is synchronized with the feed roller 4, which feeds the body blanks A into position, so that the wrapper blanks B are properly superimposed over and are in registry with the successive advancing body blanks A. The diameter of the feed roller 37 is the same as that of the feed roller 4 and it operates to feed one wrapper blank during each revolution thereof. The wrapper feed roller 37, driven in unison with the body feed roller 4, is so synchronized as to place the bottom section a' of the wrapper blank in registered position over the bottom section a of the body blank, as illustrated in Fig. 7. It will be noted that the lower end 22 of the inclined rear wall 2 of the chute feeding the body blanks A is so positioned relative to the feed roller 4 as to feed only one blank at a time into position on the belt 11 with each rotation of the feed roller 4. Likewise, the lower end 23 of the inclined rear wall 35 of the feed chute containing the wrapper blanks B is so positioned relative to the feed roller 37 as to feed only one wrapper blank at a time onto the belt 11 with each rotation of the roller 37.

70 It will be noted that the width of the belt 11 is approximately the same as the width of the bottom section a of the body blank A, so that the side wall section b of the body blank overhangs the side edges of the belt.

75 Means are provided for insuring proper reg-

istry of the wrapper blank B with the body blank A. By referring more particularly to Figs. 4, 5 and 17, it will be noted that a pair of blank abutment members 46 are provided which are pivotally mounted at one end thereof upon a fixed shaft 5. The blank-engaging members 46 are each provided with a downwardly projecting leg 48 whose end portions 49 operate to periodically engage the advancing tabs d of the body blank A. At this stage of the operation the adhesive x 10 on the bottom section a of the body blank is still green, and the feed roller 37 operates to move the wrapper blank along the top surface of the body blank until the corner tabs d' of the wrapper blank abut the end portions 49 of the blank-engaging members 46, thus bringing the corner tabs d' of the wrapper blank into alignment with the corner tabs d of the body blank.

15 The blank-engaging members 46 are manipulated into and out of blank-engaging position by 20 means of a cam 55 fixed to a suitable shaft 63 rotatably mounted in the framework 1 of the machine. A sprocket wheel 57 fixed to the cam shaft 63 is driven by a drive chain 58 trained over a sprocket wheel 59 fixed to the driven shaft 38 25 of the feed roller 37. A reciprocating rod 51 reciprocating in a guide sleeve 52 fixed to the framework 1 of the machine is provided with a roller 53 at one end thereof, which rides over the surface of the cam 55. The cam 55 is provided 30 with a surface projection 56 which operates to raise the rod 51 upwardly as it rides over the cam projection 56. The rod 51 is pivotally connected by pin 50 to one of the pivotally mounted blank abutment members 46. If desired, two 35 cams 55 on each side of the belt 11 may be provided both driven by the drive chain 58, in which event two reciprocating arms 51 may be provided each connected to the adjacent blank abutment member 46.

40 It will be appreciated that as the roller 53 passes over the surface projection 56 of the cam 55 the lower end 49 of the abutment members 46 will be raised out of contact with the blank assembly, so as to permit the blank assembly to 45 pass under the leg portions 48 thereof. As the next succeeding blank assembly approaches the leg portions 48 of the abutment members 46, the roller 53 will move into contact with the depressed portion 60 of the cam 55 so as to bring the end 50 portion 59 of the abutment members 46 into position to engage the corner tabs d of the next succeeding advancing body blank to effect proper registration of the wrapper blank upon the body blank. The end portions 49 of the abutment 55 members 46 thus halt the advancing movement of the body blank for a predetermined interval until registration of the wrapper blank and the body blank has been effected. The abutment arms 46 also operate to effect proper uniform spacing of 60 the blank assemblies upon the upper run 11 of the belt, which becomes important in effecting operations later to be performed on the blank assembly.

65 To further properly align the blank assemblies upon the belt 11, a pair of stationary guide members 61 along each side edge of the belt 11 may be provided. The guide members 61 may be flat strips of metal which are flared as at 62 at the advance end thereof to permit free entry of the 70 blank assemblies therebetween. The guide members 61 further operate to properly align the wrapper blank upon the body blank.

75 As the blank assembly moves forward beyond the control of the end portions 49 of the blank 75

abutment members 46, the bottom section *a'* of the wrapper blank has then been properly registered with and secured to the bottom section *a* of the body blank, and the blank assembly, comprising the combined body blank and wrapper blank, is then ready for further treatment.

The side wall gluing and wrapping mechanism

After the blank assembly has moved beyond the control of the end portions 49 of the blank abutment members 46, it passes into that part of the machine which, for ease in description, has been designated the side wall gluing and wrapping mechanism, which mechanism is illustrated more particularly in Figs. 6 and 7. This mechanism comprises more particularly a continuous blank-supporting belt 87 which is trained over the guide sheaves 86, 88, 89 and 90 so that the top flight of the belt extends in a substantially horizontal direction. The belt-supporting sheaves 88 and 89 may be offset to make room for other operating mechanism which will be presently described. The guide sheaves 86, 88, 89 and 90 may be mounted upon suitable shafts which rotate in suitable bearings provided in the framework 1.

An upper blank-retaining belt 77, similar to the lower blank-supporting belt 87, is trained over guide sheaves 75, 78, 79, 80 and 81 in such a manner that the lower flight of the belt extends parallel with and in close proximity to the upper flight of the conveyor belt 87. The guide sheaves 75, 78, 79, 80 and 81 may be suitably mounted upon shafting journaled to the framework 1. The upper conveyor belt 77 may be positively driven by means of a sprocket wheel 83 fixed to a shaft 76 upon which the belt sheave 75 is mounted. The sprocket wheel 83 is operatively connected to sprocket wheel 85 fixed to the driven shaft 38 by means of a chain belt connection 84. If desired, the sheave 86 supporting the lower conveyor belt 87 may also be positively driven by means of a gear 91 fixed to shaft 87' which supports the sheave 86, the gear 91 meshing with gear 92 attached to the shaft 76 which supports the sheave 75. The upper flight of the lower conveyor belt 87 and the lower flight of the upper conveyor belt 77 are so arranged as to grip the blank assembly therebetween and to positively feed the blank assembly forwardly as it emerges from the control of the blank abutment members 46. It will be appreciated, however, that it may be necessary to positively drive only belt 77 or belt 87, one belt then being driven by the other through frictional contact between the blank assembly and the adjacent flights of the belts.

As the blank assembly advances between the adjacent flights of the conveyor belts 77 and 87, a pair of spaced glue rollers 93 are provided to apply a strip of adhesive *y* to the side wall flaps *b''* of the wrapper blank. The glue rollers 93 are fixed to a shaft 94 rotatably mounted in the framework 1 of the machine. The shaft 94 may be positively driven by gearing or other power transmission mechanism operatively connecting the shaft 94 to the driven shafts 91 or 76. Each of the glue rollers 93 extends into a glue pot 90 containing liquid glue which is picked up by the rotating glue rollers 93 and deposited in a defined strip *y* along the side wall flaps *b''* of the wrapper blank. It will be appreciated that the conveyor belts 77 and 87 are of a width approximately equal to the width of the bottom section *a* of the body blank, so that the side wall sections *b* of the body blank and the side

wall flaps *b''* of the wrapper blank overhang the side edges of the conveyor belt, thus permitting free application of the adhesive to the side wall flaps *b''* of the wrapper blank by the glue rollers 93. It is also understood that the glue rollers 93 are properly spaced with reference to the width of the wrapper blank so as to apply the glue strip *y* only to the side wall flaps *b''* of the wrapper blank. If the wrapper blank is of substantial stiffness it may be unnecessary to positively drive the glue rollers 93, since the relatively stiff side wall flaps *b''* of the wrapper will frictionally engage the peripheral surface of the glue rollers 93 sufficiently to rotate them so as to insure positive application of the glue strip *y* thereto.

Following the application of the glue strip *y* to the side wall flaps *b''* of the wrapper, mechanism is provided to fold the side wall flaps *b''* of the wrapper downwardly and then fold the adhesive surface *y* of the side wall flaps *b''* against the lower face of the side wall sections *b* of the body blank. Referring more particularly to Figs. 6, 7 and 20, a pair of folding arms 100 are provided which are so spaced and positioned as to ride over the side wall flaps *b''* and press the same downwardly, as more particularly illustrated in Fig. 20. The flap folding arms 100 are spaced a distance substantially equal to the width of the bottom section *a* and side wall sections *b* of the body blank and are fixed to a shaft 103 rotatably mounted in suitable journals 105 provided on the framework 1 of the machine. During the passage of the blank assembly into position between the folding arms 100 they are held in raised tilted position, as illustrated in dotted lines in Fig. 7, and when the blank is properly positioned between the folding arms 100, mechanism is provided to pivot the arms 100 downwardly and with this downward stroke effect a downward bending of the side wall flaps *b''* of the wrapper around the outer edge of side wall sections *b* of the body member. The up and down swinging movement of the folding arms 100 is positively effected by means of a lever 104 fixed to the shaft 103 which fixedly supports the folding arms 100. The outer end of the lever 104 is pivotally connected to an upwardly reciprocating rod 106 which carries a roller 108 at the lower end thereof. The roller 108 rides over the cam surface of the cam member 109 fixed to a driven shaft 111, which shaft may be operatively connected by suitable gearing, drive chain or other transmission mechanism, to a driven shaft in the machine. A guide block 107 fixed to the framework 1 of the machine guides the reciprocating movement of the rod 106.

The cam 109 is provided with a projection 110 on the cam surface thereof, which operates to raise the rod 106 upwardly when the roller 108 carried by the rod rolls over the cam projection 110. Upward movement of the rod 106 operates to swing the folding arms 100 from upward tilted position downwardly when the blank assembly is in proper position therebetween. It will be noted that the cam projection 110 is of relatively limited extent so that the folding arms 100 are quickly swung down and swung up, and the folding arms 100 are normally held in upward tilted position for a sufficient period of time to permit the blank assembly to move therebetween. The folding arms 100 are provided with a rounded corner 102 which corner first contacts the side wall flaps *b''* and is so shaped as not 75

to interfere with the normal advance of the blank assembly into position between the paired folding arms 100.

From the folding arms 100 the blank is conveyed between the adjacent flights of the conveyor belts 77 and 87 through a pair of spaced wrapping arms 112, which are illustrated in Figs. 6, 7 and 21. The wrapping arms 112 are spaced a distance equal to the combined width of the bottom section *a* and side wall sections *b* of the body blank and are arranged in generally parallel relation so as to fold the side wall flaps *b''* of the wrapper blank around the free edge of the side wall sections *b* of the body blank and into adhesive contact with the under surface of the side wall sections *b*. The spaced wrapping arms 112 are each provided with a flared mouth portion 113 to facilitate the passage of the blank assembly into position between the spaced wrapping arms 112. The lower edge of the wrapping arms 112 are gradually inturned in the direction of advance of the blank assembly so as to provide a gradually inturned flange 114. The inturned flange 114 operates to fold the side wall flaps *b''* of the wrapper blank around the free edge of the side wall section *b* of the body blank and inwardly against the under face of the side wall sections *b*, so that the adhesive *y* on the side wall flaps *b''* will adhere to the under face of the side wall sections *b* of the body blank. Fig. 21 illustrates generally the manner in which this operation is effected.

When the blank assembly leaves the conveyor belts 77 and 87 the bottom section *a'* of the wrapper blank has been fixedly secured to the bottom section *a* of the body blank and the side wall flaps *b''* of the wrapper blank have been adhesively secured to the under or inside face of the side wall sections *b* of the body blank, the side wall sections *b''* of the wrapper blank being unsecured to the side wall sections *b* of the body blank. The blank assembly then moves into engagement with the side wall stretching mechanism.

45 Side wall stretching mechanism

It will be appreciated that if the wrapper blank were tightly wrapped around the outside face of the out-stretched side wall sections *b* of the body blank and fixedly held, the wrapper blank might tear or rupture when the side wall sections of the body blank are folded generally at right angles to the bottom section of the box. In accordance with this invention, mechanism is provided for stretching the wrapper blank by bending the side wall sections of the blank assembly at an angle to the bottom section of the blank assembly before the adhesive *y* on the side wall sections has become dried and fixed to permit the side wall flaps *b''* of the wrapper blank to slip slightly, if necessary, over the inside face of the side wall sections of the body blank so that the side wall sections *b'* of the wrapper blank will smoothly cover the outside face of the erected side wall sections *b* of the body blank without rupturing the wrapper blank. The side wall stretching mechanism is illustrated more particularly in Figs. 8 and 9 and is diagrammatically illustrated in Fig. 22.

70 As the blank assembly is discharged from the conveyor belts 77 and 87 it passes between paired rollers which operate to flex the side wall sections *b* of the body blank downwardly and thus stretch the side wall sections *b'* of the wrapper blank. A pair of spaced rollers 120 are fixedly

mounted upon a shaft 122, which shaft is rotatably mounted in suitable bearings provided in the framework 1 of the machine. The shaft 122 and the spaced stretching rollers 120 may be positively driven by means of a sprocket wheel 132 fixed to one end of the shaft 122, which is driven by a drive chain 133 trained over a sprocket wheel 134 fixed to one end of the driven shaft 126. The stretching rollers 120 are spaced a distance approximately corresponding to the space 10 between the side wall sections *b* of the body blank. The stretching rollers 120 wheel over the side wall sections *b'* of the wrapper blank and the side wall sections *b* of the body blank, and are also provided with a beveled peripheral surface 121 which defines the angle of bend of the side wall sections of the blank assembly.

A pair of cooperating stretching rollers 120' are positioned directly beneath the pair of stretching rollers 120 and are similar thereto in size and spacing. The stretching rollers 120' are supported upon a shaft 121 which may be rotatably mounted in the framework 1 of the machine. The outer periphery of the stretching rollers 120' are provided with a beveled surface 121' which may match the beveled surface 121 of the stretching rollers 120. It is thus seen that as the blank assembly moves between and is held between the upper pair of stretching rollers 120 and the lower pair of stretching rollers 120', the side wall sections *b* are bent downwardly to stretch over the side wall sections *b'* of the wrapper blank to effect any necessary slippage of the side wall flaps *b''* or adjustment of the wrapper blank before the green adhesive *y* becomes dry and fixed. The stretching rollers 120' need not be positively driven but may be rotated by frictional contact with the side wall sections of the blank assembly which is positively advanced by the stretching rollers 120.

Any desired number of paired cooperating stretching rollers may be provided to effect proper stretching of the wrapper blank around the side wall sections of the body blank. Three cooperating pairs of stretching rollers are shown in the machine illustrated in Figs. 1, 8 and 9. Thus a pair of spaced stretching rollers 123, immediately following the stretching rollers 120, may be provided which are fixed to a shaft 125 rotatably mounted in the framework 1 and positively driven by a sprocket wheel 137 fixed to the shaft 125 and driven by a drive chain 136 trained over the sprocket wheel 135 fixed to one end of the driven shaft 122. The peripheral surface of the stretching rollers 123 are also beveled as at 45 124 so as again downwardly flex or bend the side wall sections *b* of the blank assembly. A pair of stretching rollers 123' whose peripheral surfaces 124' are beveled to match the peripheral surfaces 124 of the stretching rollers 123 may be provided, the rollers 123' being fixed to a shaft 125' rotatably mounted in the framework 1. The blank assembly in its forward movement is drawn in between the cooperating stretching rollers 123 and 123' which again stretches the side wall sections 50 of the blank assembly.

If further stretching of the side wall sections of the blank assembly is desired, additional cooperating pairs of stretching rollers may be provided. The third set of stretching rollers, illustrated in Figs. 8 and 9, comprise the spaced rolls 126 having beveled bending surfaces 127, these rolls being fixed to a shaft 128 rotatably mounted in the framework 1 of the machine. As shown 55 more particularly in Fig. 3, the shaft 128 may be 60

driven by a sprocket wheel 140 fixed to the shaft 128 which is driven by a drive chain 139 trained over a sprocket wheel 138 attached to the driven shaft 125. An additional pair of stretching rollers 5 126' cooperating with rollers 126 are positioned beneath the advancing blank assembly, stretching rollers 126' being provided with beveled surfaces 127' which match beveled surfaces 127 of the rollers 126. The stretching rollers 126' may 10 be mounted upon a shaft 128' rotatably mounted in the framework 1 of the machine.

It will be appreciated that surfaces 121 and 121' of the stretch rolls 120 and 120', surfaces 124 and 124' of stretch rolls 123 and 123', and surfaces 127 and 127' of stretch rolls 126 and 126', 15 may be beveled at varying degrees so as to effect the proper stretching of the wrapper blank around the side wall sections b of the body blank so that when the adhesive y has become dried, 20 the wrapper blank will not tear or rupture when the side wall sections of the blank assembly are erected into their ultimate position at right angles to the bottom section. It will be noted that this stretching operation is performed while the adhesive y on the side wall flaps b'' of the wrapper 25 blank is still green or wet, permitting, if necessary, a slight slippage of the liquid glue-coated side wall flaps b'' over the inside surface of the side wall sections b, so that the side wall sections b' 30 of the wrapper blank will have sufficient area to fully cover the outside surface of the side wall sections b of the body blank without tearing or rupturing the wrapper when the side wall sections b of the body blank are folded at right angles 35 to the bottom section a.

When this stretching operation has been completed, the blank assembly passes between two pairs of cylindrical rollers which operate to press the side wall flap b' to the wrapper blank into firm adhesive contact with the inside face of the side wall sections b of the body blank. A pair 40 of spaced cylindrical rollers 130 are fixed to a shaft 131, which shaft carries a sprocket wheel 143 driven by drive chain 142 trained over sprocket wheel 141 fixed to the driven shaft 128. Two cooperating presser rolls 130', similar in 45 construction to presser rolls 130, are positioned beneath the rollers 130. Rollers 130' are fixed to a shaft 131' rotatably mounted in the framework 1 of the machine. The presser rolls 130 and 130' cooperate to press the side wall flaps b'' of the wrapper blank into adhesive contact 50 with the side wall sections b of the body blank and further act to smooth or iron out the side wall sections b' of the wrapper blank. The stretching rolls 120', 123' and 126' need not be 55 positively driven but are rotated by the action of the driven stretching rolls 120, 123 and 126 respectively. Likewise, presser rolls 130' need not be directly driven but are caused to rotate by the action of the positively driven presser rolls 130 superimposed thereover.

At this stage in the manufacturing operation, the blank assembly may be further compressed 60 to flatten out the blank and secure positive adhesion between the bottom wall section of the body blank and wrapper blank and the side wall flaps b'' of the wrapper blank and the side wall sections b of the body blank. This mechanism 65 may comprise a pair of spaced ironing rollers 146 and 146' between which the blank assembly is compressed. The compression roller 146 may be fixed to a supporting shaft 147 rotatably mounted in the framework 1. The cooperating 70 compression roller 146' may be fixed to a shaft 75

147' rotatably mounted in the framework 1. The compression roller 146 may be positively driven by the provision of a sprocket wheel 148 fixed to one end of the shaft 147 over which is trained a drive chain 149 which is trained over a sprocket 5 144 fixed to the driven shaft 131, as illustrated in Fig. 3.

As the blank assembly emerges from the compression rollers 146 and 146', the bottom section a' and the side wall sections b' of the wrapper blank have been adhesively secured and fixed to the bottom section a and the inside face of the side wall sections b, respectively, of the body blank and, in addition, the wrapper has been suitably stretched over the side wall sections b 15 of the body blank, so that when the side wall sections b of the body blank are erected into position at right angles to the bottom section a, the wrapper blank will neatly and smoothly cover the bottom section and the side wall sections of the 20 body blank without break or rupture.

In the manufacture of applicant's set-up blank by the method and apparatus herein disclosed, a substantial saving in shipping and storage costs can be effected if the blank assembles as they 25 emerge from the compression rollers 146 and 146' are packed in the flat by the box manufacturer and thus shipped to the user, the remaining box-assembling operations then being performed by the user of the box. Since the finished box is 30 of the set-up type and not generally collapsible, it obviously occupies more space in shipment and storage when fully set up than when shipped and stored as a flat blank unit. My apparatus is 35 highly adapted to be separated into two divisions, 40 wherein the first division of the apparatus, as heretofore described, may be used by the box manufacturer and the second division of the apparatus, to be presently described, used by the goods manufacturer to perform the final box-assembling operation prior to the packaging of 45 the goods in the box. The second division of the apparatus and its method of operation will now be described.

End wall bending mechanism

The end wall bending mechanism is mounted upon a framework 150 which is preferably arranged generally at right angles to the framework 1 previously described, if the entire box-assembling operation is to be performed at the box plant on one machine unit. It will be appreciated, however, that if the framework 150 and its operating mechanism, presently to be described, is not directly associated with the framework 1 and its operating mechanism, it may be arranged in any convenient position in the box-assembling plant.

A pair of spaced blank assembly supports 151 are provided which are carried by the framework 150 and are provided with flat surfaces along 55 which the blank assembly may slide. The blank assembly is moved along the supports 151 by a pair of spaced parallel extending conveyor belts or chains 153 positioned between the supports 151. The conveyor chains or belts are trained over a pair of guide sheaves or sprocket wheels 152 fixed to a shaft 154 rotatably supported on the framework 150 at one end of the blank supports 151 by suitable brackets 155. The blank- 60 advancing chains or belts 153 are also trained over a pair of guide sheaves or sprocket wheels 156 which are fixed to a shaft 157 rotatably mounted in the framework 150, the sprocket wheels 156 being positioned adjacent the other end of the 65 70 75

blank supports 151. The blank-advancing chains 153 may be driven by power means applied to the shaft 154. For purposes of illustration, there is shown in Fig. 3 a bevel gear 145 fixed to the shaft 154 which meshes with bevel gear 145' fixed to the driven shaft 131, previously described. Any suitable power means, however, may be used to drive the blank-advancing belt or chains 153.

As illustrated more particularly in Figs. 8 and 9, the blank assembly is supported upon the spaced supports 151 with the wrapper blank uppermost, the side edges of the spaced supports 151 being so arranged that the end wall sections c of the body blank and the corner tabs d of the body blank overhang the side edge of the spaced supports. The blank-advancing belts or chains 153, positioned between the supports 151, are each provided with spaced lugs 158 which are arranged in pairs. The lugs 158 are so spaced around the advancing chains 153 that each pair of lugs 158 will engage the wrapped side wall sections at the rear of the blank assembly and move the blank assembly forwardly along the spaced blank supports 151. The lugs 158 may be adjustably connected to the advancing chains or belts 153 so as to advance the blank assemblies in the proper spaced relation along the supports 151.

As the blank assemblies move along the spaced supports 151, they come into contact with means for folding the end wall flaps c' of the wrapper blank downwardly over the edge of the end wall sections c of the body blank. As illustrated more particularly in Figs. 10 and 11, a pair of spaced flap-folding discs 160 are provided for this purpose, the discs 160 being fixed to a shaft 161 rotatably mounted in the framework 150. The folding discs 160 are positively driven in synchronism with the blank-advancing chains 153 by means of a sprocket wheel 162 fixed to one end of the shaft 161 and driven by a drive chain 163 trained over a sprocket wheel 164 fixed to the driven shaft 154. The peripheral extent of the folding discs 160 is somewhat greater than the width of the blank assembly, the folding discs 160 each having a peripheral cam surface 165 which contact the end wall flaps c' of the wrapper to fold the same downwardly, in the manner illustrated in Figs. 11 and 24. The peripheral surface 165 has a peripheral length approximately corresponding to the length of the end wall flaps c'. A notch 166 is cut out from the periphery of each of the folding discs 160 which is equal in peripheral extent to the predetermined spacing between the ends of the side wall flaps b' of adjacent blanks moving along the supports 151. Thus the peripheral surfaces 165 of the folding discs 160 only operate to fold the end wall flaps b'' downwardly. The initial bending of the end wall flaps c'' by the folding discs 160 serve to initially flex the same preparatory to further folding operations to be presently described.

Means are provided for folding the corner tabs d in a downward direction. As shown more particularly in Figs. 10, 11 and 25, a pair of radially extending folding arms 170 fixed to a shaft 172 operate to fold the corner tabs d at the advancing end of the blank assembly in a downward direction, and a pair of folding arms 171 also fixed to the shaft 172 operate to fold the corner tabs d at the following end of the blank in a downward direction. The shaft 172 is rotatably mounted in the framework 150 and is rotated by a sprocket wheel 173 fixed to one end of the shaft 172. A drive chain 174 is trained over the sprocket wheel 175 fixed to the driven

shaft 161, previously described. The ends 176 of the folding arms 170 are so spaced and shaped as to engage only the corner tabs at the advancing end of the blank as the arms 170 rotate in a counterclockwise direction as viewed in Fig. 11. The end portions 177 of the folding arms 171 are so shaped and spaced as to engage the corner tabs at the following end of the blank assembly. It is thus seen that the arcuate spacing of the ends 176 and 177 of the folding arms 170 and 171 is approximately equal in linear distance to the length of the end wall sections c of the body blank. The speed of rotation of the shaft 172 carrying the folding arms is synchronized with the speed of rotation of the folding discs 160 so as to place the ends 176 and 177 of the folding arms 170 and 171 respectively in proper registry with the corner tabs of the blank assembly as the blank advances thereunder.

The end wall gluing mechanism

It will be noted that the ends 176 of the folding arms 170 during their arcuate travel remain in engagement with the corner tabs at the advancing end of the blank assembly for a predetermined distance of forward travel of the blank assembly along the supports 151. Prior to the release of the corner tabs at the advancing end of the blank assembly from the folding section of the folding arms 170, they are engaged by a pair of spaced tab-retaining guides 180 each provided with a flared mouth 181 to facilitate the entry of the corner tabs between the tab-retaining guides 180 and the side edge of the adjacent blank support 151. Similarly, the corner tabs at the following end of the blank assembly are held in downwardly folded position by the folding arms 171 until engaged by the flared mouth 181 of the adjacent tab-retaining elements 180. As the blank assembly continues to move between the tab-engaging elements 180 they are held in downwardly folded position substantially at right angles to the bottom section of the blank assembly.

While the corner tabs of the blank assembly are held in a downwardly folded position by the tab-retaining elements 180, adhesive is applied to the under face of the end wall flaps c'' of the wrapper blank. The adhesive is applied in the form of a strip z to the under face of the end wall flaps c'' only by a pair of spaced glue rollers 182 fixed to a shaft 183 rotatably mounted in suitable bearings. Each of the glue rollers 182 extends into a pool of liquid glue contained in a glue pot 184. If desired, the shaft 183 may be positively driven by a suitable mechanism, or if the wrapper blank is of sufficient stiffness the passage of the end wall flaps c'' of the wrapper blank will operate to rotate the glue rollers 182 to apply adhesive to the under surface thereof. It will be noted that the glue rollers 182 are of such width as to apply a strip of adhesive z to the end wall flaps c'' only and that during this operation the corner tabs are held in a downwardly extending direction by the tab-retaining element 180 and out of contact with the adhesive coated surface of the glue rollers 182.

After the blank assemblies have passed over the glue rollers 182 they are ready for erection into box-forming position by the box-assembling mechanism.

The box-assembling mechanism

The mechanism for erecting the prepared blank assembly into set-up box form is illustrated more particularly in Figs. 12, 13, 14, 15 and 27. The

box-assembling mechanism operates to fold the corner tabs *d* into a position substantially at right angles to the side wall sections of the blank assembly, then to fold the side wall sections substantially at right angles to the bottom section, then to fold the end wall sections substantially at right angles to the bottom wall section, and finally to fold the end walls flaps *c* of the wrapper blank inwardly and into adhesive contact with the inside face of the end wall sections, producing a box as illustrated in Fig. 32.

The box-assembling mechanism comprises more particularly a blank-supporting platform 200 supported on a reciprocating plunger 205. The platform 200 presents a flat blank-supporting surface having an area closely approximating the inside area of the bottom section of the box to be assembled. The platform 200 at its lowermost position of movement seats within a cell structure 201 having surrounding side wall flange portions 202. Mechanism is provided for shoving the successive blank assemblies over the top edge 203 of the cell flanges 202 when the top surface of the platform 200 is slightly below the top edge 203 of the cell flanges 202.

The mechanism for advancing the blank assembly onto the platform 200 is illustrated more particularly in Figs. 10 and 11. A pair of pusher arms 190, positioned between the supports 151 in spaced relation, are operatively connected at one end thereof to a connecting bar 189. A bell crank lever 191 pivotally mounted upon a fixed stub shaft 192 has one arm thereof pivotally connected to the connecting bar 189, the other arm carrying a roller 193. The roller 193 is positioned to ride over the cam surface of a cam 194 which is fixed to a shaft 195 rotatably supported by the framework 150 of the machine. The cam surface of the cam 194 is so shaped as to periodically rock the bell crank lever 191 so as to reciprocate the pusher arms 190 in a generally horizontal direction, the pusher arms 190 being suitably supported upon guide plates 196. The pusher arms at the free end thereof are provided with a nose portion 197 which is designed to seat under the rear wrapped side wall section of the blank assembly as it is moved forwardly by the advancing chains 153. The lower edges of the pusher arms 190 are each provided with a cam surface 199, which cooperates with the guide plate 196 to raise a finger 198 projecting upwardly from the nose portion 197 into contact with the rear side edge of the advancing blank assembly and with a continued forward reciprocation of the pusher arms 190 the blank is pushed into position onto the supporting platform 200. A tension spring 188 connected to the bell crank lever 191 operates to maintain the roller 193 in constant contact with the cam surface of the cam 194. Thus when the roller 193 rolls over the cam surface 187, the tension spring 188 operates to reciprocate the pusher arms 190 forwardly into engagement with the rear side edges of the blank assembly and to push the blank onto the platform 200. With a continued clockwise rotation of the cam 194, the roller 193 will ride over the cam surface 186 to rock the bell crank lever rearwardly and draw the pusher arms 190 rearwardly into position to engage the rear side edge of the next succeeding blank assembly discharging from the blank supports 151.

The cam shaft 195 is preferably operably connected to gearing, chain drive or other power transmission mechanism, to the driven shaft 157 supporting the sprocket wheels 156. By way of

example, the power transmission mechanism, as shown in Fig. 11, may comprise a sprocket wheel 159 attached to driven shaft 157, over which is trained a drive chain 185 which is trained over a sprocket wheel 179 fixed to the cam shaft 195. By means of this or similar drive mechanism, it will be noted that the pusher arms 190 are reciprocated to engage and advance the successive blank assemblies in timed relation to the discharge of the blank assemblies from the advancing chains 153.

Referring again to Figs. 12, 13, 14, 15 and 27, it will be noted that when the pusher arms 190 have positioned a blank assembly upon the platform 200, the platform-supporting reciprocating plunger 205 is moved upwardly into the cell structure 201. The plunger 205 may be moved upwardly by the action of suitable driving mechanism operated by a rotating cam (not shown) which is rotated in timed relation to the rotation of the cam shaft 195.

The flanges 202 of the cell structure are dimensioned to approximate the inside contour of the box to be assembled. A box-forming frame is provided which comprises a pair of spaced side wall elements 206 each having an outwardly flared mouth portion 207 which permits the free insertion of the blank assembly therein. Attached to each end of the side wall forming elements 206 is a shoe 208 which projects slightly below the lower edge thereof. Each shoe 208 is so shaped as to bend the corner tabs *d* of the blank assembly downwardly to a position substantially at right angles to the outwardly flared side wall sections *b* of the blank assembly during the initial upward movement of the blank-supporting platform 200. As the blank-supporting platform continues its upward movement, the outwardly flared side wall sections *b* of the blank assembly come into contact with the outwardly flared mouth portions 207 of the side wall folding elements 206, and as the platform 200 continues its upward movement the side wall sections *b* of the blank assembly are folded substantially at right angles to the bottom section *a* of the blank assembly, in which position the previously downwardly folded corner tabs *d* extend in an inwardly direction, as illustrated more particularly in dotted lines in Fig. 13. Thus it is seen that at this stage of the upward movement of the platform 200, the side wall sections *b* have been folded into box-forming position substantially at right angles to the bottom section *a* and the corner tabs *d* have been folded inwardly. The side wall folding elements 206 may be fixed to a reinforcing frame 209 at the upper edge thereof which is fixedly supported by means of suitable bracket supports 209.

A pair of end wall folding elements 220 are provided which operate to fold the end wall sections *c* of the blank assembly downwardly substantially at right angles to the bottom section *a* of the box being formed during the upward movement of the platform 200, which is performed after the side wall sections *b* have been folded downwardly or during the downward folding movement of the side wall sections *b* but not prior thereto. The lower edge of the end wall folding elements 220 are flared outwardly as at 223 to provide a mouth which permits easy entry of the end wall sections *c* therebetween. Due to the folding action which the end wall flaps *c* have received previously by the folding discs 160 and the end wall folding elements 220, the end wall flaps *c* will project inwardly over the end 75

wall sections *c* when the end wall sections *c* have been folded at right angles to the bottom section *a*. At this point the cell member 201 moves upwardly so as to project the flanges 202 thereof 5 into telescoped position within the side and end wall sections of the box partly formed. During the upward movement of the cell member 201, the upper edge 203 of the flanges 202 will engage the inturned end wall flaps *c''* and fold them inwardly and upwardly into adhesive contact with 10 the inside face of the end wall sections *c* of the body structure of the box. The sides 212 of the flanges 202 will serve to iron the upturned end wall flaps *c''* into positive adhesive engagement 15 with the inside face of the end wall sections *c* and inturned tabs *d* of the box body.

The cell member 201 may be supported on a vertically reciprocating tube 213 which surrounds the plunger 205, the cell structure 201 being attached to the upper end of the reciprocating tube 213 by means of a suitable boss 214 and a set screw 215. The cell member 201 and the tubular member 213 may be reciprocated upwardly and downwardly through the action of a cam member (not shown) operatively connected thereto, which cam member is driven in synchronism with the cam member which drives the reciprocating plunger 205.

The platform 200 moves upwardly until the 30 bottom section *a* of the box comes into contact with the inwardly projecting stop flanges or anvils 221 projecting inwardly from the end wall folding elements 220. When the bottom section 35 of the box has been moved upwardly into abutment with the stop flanges 221 the box has been assembled generally as it appears in Fig. 30, with the wrapped side wall sections *b* and the wrapped end wall sections *c* extending downwardly at right angles to the bottom section *a* and with the corner tabs *d* turned inwardly so as to lie against 40 the inside face of the end wall sections *c*. The cell member 201 then moves upwardly and the partially inturned end wall flaps *c''* are engaged by the rounded upper edge 203 of the flanges 202 45 of the cell member, which operates to force the end wall flaps *c''* inwardly and upwardly and into adhesive contact with the inside face of the end wall sections *c*, when the flanges 202 of the cell member have arrived at their extreme upward movement, as illustrated in dotted lines in Fig. 13. 50 The cell member 201 is then drawn downwardly by its supporting tube 213 and the operating mechanism which reciprocates with the tube. The downward movement of the cell member 201 55 is followed by the downward movement of the platform 200 at a spaced distance therefrom to a point where the completed box, as illustrated in Fig. 32, can be kicked out from the forming frame. The platform 200 continues its downward movement until it is seated within the cell member 201, in which position the pusher arms 190 operate to advance a second blank assembly into position upon the platform 200.

Method of assembly

65 The method and the steps employed in assembling the wrapped box is more particularly illustrated in Figs. 16 to 32 inclusive. It is understood that the wrapped box can be assembled by 70 other apparatus than that particularly disclosed in the drawings and above described. It is therefore understood that the method and arrangement of steps for assembling the box can be effected by other types of automatic assembling 75 mechanism than that specifically disclosed.

In manufacturing and assembling the wrapped box, large sheets or rolls of suitable cardboard are cut and scored to the desired shape and size to provide the body blanks. The body blanks may be formed from a relatively cheap cardboard which should have the characteristic of substantial stiffness. The body blanks may be cut and scored to provide a bottom section of any desired rectangular shape and area, to which are hinged, as by scoring, the blank, the side wall sections *b*, 10 the corner tabs *d* hinged thereto, and the end wall sections *c*. The side wall sections *b* and the end wall sections *c* may be any desired width to provide a finished box of the desired depth.

The wrapper blank *B* is cut to the required 15 shape to properly wrap the body blank on an automatic cutting machine. Preferably, the wrapper blank is not scored, so that the wrapper blank possesses full strength around the edges and corners of the box. The wrapper blank may be 20 formed from any desired relatively tough but bendable material, such as a tough Kraft paper or a relatively light but tough and flexible finished cardboard which has the necessary bending qualities. The wrapper blank when glued 25 and applied to the body blank provides an assembled box which is sturdy and relatively unflexible and highly resistant to twisting or bowing strains. The box as produced by my improved method has all the strength and serviceability of 30 a wrapper box assembled by slower methods.

For example, wrapped boxes made on the well known Stokes and Smith wrapping machine in general use, require complete assembly of the body structure of the blank on a corner-staying 35 machine, on which only a few hundred box bodies per hour can be assembled. The assembled box bodies must then be transferred and hand-fed into the Stokes and Smith wrapping machine, on which only a few hundred boxes per 40 hour can be assembled. By my improved method the assembly operation can be performed on a single machine at the rate of several thousand boxes per hour so that the boxes can be produced at a cost comparable to unwrapped folding boxes 45 which cannot be made to present the rigidity and strength required for the packaging of certain classes of merchandise, such as hosiery, wearing apparel, and similar merchandise, where the boxes are piled to considerable heights one upon 50 the other and considerable strain is thus placed on the lowermost boxes.

Referring more particularly to Figs. 16 to 32 inclusive, the prepared body blank *A* is first fed into contact with a suitable glue roller which 55 operates to apply a layer of adhesive *x* to one face of the bottom wall section *a* only. The wrapper blank *B* is then fed into superimposed position over the body blank with suitable means provided to insure proper registry of the bottom wall section *a'* of the wrapper blank with the bottom wall section *a* of the body blank.

The blank assembly then continues to move along a suitable conveyor upon which it is firmly held, as by a traveling belt 11. The blank assembly is so positioned upon the moving conveyor that the side wall sections *b* of the body blank and the side wall flaps *b''* of the wrapper blank overhang the side edges of the traveling conveyor so that the adhesive-applying means, 70 such as glue rollers 93, are in position to apply a strip of adhesive *y* to one face only of the side wall flaps *b''* of the wrapper blank, as illustrated in Fig. 19.

The blank continues to move into contact with 75

side wall folding and wrapping elements which first operate to fold the side wall flaps b'' around the free edge of the side wall sections b of the body blank, as shown in Fig. 20, and then operate to continue the folding of the side wall flaps b'' into adhesive contact with the inside face of the side wall sections b of the body blank, as illustrated in Fig. 21.

Upon further advance movement of the blank assembly the wrapped side wall sections b are then bent or stretched while the adhesive y is still green or wet, so as to insure the proper stretching of the side wall sections b' of the wrapper blank so that they will smoothly but fully cover the outside face of the side wall sections b of the body blank when the box is finally erected, without causing the wrapper to tear or split when the side wall sections b are eventually folded into a position at right angles to the bottom section a . After the stretching operation the side wall flaps b'' are ironed into fixed adhesive contact with the inside face of the side wall sections b of the body blank. The side wall stretching operation and the wrapper ironing operation are illustrated in Fig. 22.

At this stage the blank assembly may be given a flattening operation which may be performed by passing the blank between compression rollers 147 and 147', as illustrated more particularly in Figs. 8 and 9. If desired the blank assemblies may then be packed flat in suitable packing crates or boxes and shipped in flat condition to the ultimate user or goods manufacturer and thus substantial economies may be effected in shipping and storage costs. The remaining box-assembling operations can be conveniently performed on another section of the box-assembling machine operated in the plant of the box user. If the entire box-assembling operation is to be performed at the same location, that section of the machine which performs the final box-assembling operation can be arranged to receive the blank assemblies as they emerge from the compression rollers 147 and 147'. Thus my improved method contemplates either the partial assembly of the wrapped box by the box manufacturer and thereafter a completion of the assembly operation by the box user, or performance of the entire box-assembling operation on box-assembling apparatus at the plant of the box manufacturer.

The remaining box-assembling steps comprise the feeding of the blank assembly along a suitable conveyor, as illustrated in Fig. 23 with the end wall sections c of the body blank and the end wall flaps c'' of the wrapper blank overhanging the side edges of the conveyor. Suitable means, such as the folding rollers 160, as shown in Fig. 24, then come into play to give the end wall flaps c'' an initial bending around the free edge of the end wall sections c of the body blank. As the next step, the corner tabs are folded substantially at right angles to the side wall sections b , which may be performed by rocker arms, illustrated in Fig. 25. With the continued advance movement of the blank assembly, the corner tabs are positively held in fixed position at right angles to the side wall sections b while adhesive-applying means, such as adhesive roller 182, apply a strip of adhesive z to the end wall flaps c'' of the wrapper blank, an operation illustrated in Fig. 26.

The blank is now ready for movement into the box-erecting mechanism partly illustrated in Fig. 27. The blank assemblies are moved to a position to be operated upon by the box-erecting

mechanism by suitable advancing means such as the blank-advancing arms 198. The box-erecting mechanism first operates to fold the corner tabs d into position substantially at right angles to the side wall sections b , as illustrated in Fig. 28, and while so held the side wall sections b are folded substantially at right angles to the bottom section a , in which position the corner tabs will extend inwardly, as illustrated in Fig. 29. The box-assembling mechanism then operates to fold the end wall sections c substantially at right angles to the bottom section a and in abutting contact with the inturned corner tabs d , as illustrated generally in Fig. 30. In the next operation the box-erecting mechanism folds the end wall flaps c'' inwardly into adhesive contact with the inside face of the end wall sections c of the body structure of the box, which operation is performed while the adhesive z on the end wall flaps c'' is still green or wet, so that the end wall flaps c'' will readily adhere to the inside face of the corner tabs d and the end wall sections c of the body blank. The box structure illustrated in Fig. 31 shows the adhesive-coated end wall flaps c'' in the process of being folded inwardly against the inside face of the corner tabs d of the end wall sections c . When this operation is completed, the completely erected box, as shown in Fig. 32, is then ejected from the box-assembling machine.

In the manufacture of wrapped boxes by the method and apparatus herein disclosed, such boxes can be made by eliminating the corner tabs d entirely from the body blank A. The corner tabs d' of the wrapper blank will, of course, be operated upon in the manner previously disclosed and will be folded inwardly against the inside face of the end wall section c of the body blank.

Two boxes of the type herein disclosed are generally used by the user as a unit, one box comprising the so-called containing section and the other comprising the cover section which usually telescopes over the containing section. It is understood, therefore, that the wrapped box as herein referred to is meant to refer to either the containing section or the cover section, or both, since either section can be made following the method and the apparatus herein disclosed.

By employing my improved method of assembling wrapped boxes, a highly serviceable and rigid set-up box can be produced substantially entirely by automatic machinery at a high production rate and at correspondingly low cost. A wrapped set-up box possesses the highly desirable qualities of great stiffness and strength. Such boxes as heretofore produced have been expensive due to the high cost of assembly by methods heretofore followed. By following my improved methods of assembly, wrapped boxes can be automatically assembled substantially without hand operation at a speed of several thousand boxes per hour, so that the wrapped box can be sold at a price comparable to the unwrapped single-ply boxes which, though reasonable in cost, are unsatisfactory for the packaging of many lines of merchandise where a rigid, firm and unyielding box structure is required. In assembling boxes by the usual folding operations, it is appreciated that relatively flexible or bendable paperboard must be used, which board does not possess the requisite stiffness and rigidity that a double-ply box having a body structure of relatively stiff unyielding box board and a flexible finished covering wrapper provides.

Set-up wrapped boxes of particular size and

shape are used in large quantities for the packaging of hosiery, wearing apparel, and other articles. It is contemplated that a single machine will be used to manufacture and assemble a wrapped box of a particular size and shape. If for production reasons it is desired to make a box of different size and shape, certain of the operating elements in my improved apparatus may be shifted, adjusted or replaced by other operating elements to effect the proper assembling and wrapping of boxes of different sizes and shapes. Such necessary adjustments, shifting of parts and substitution of parts to wrap and assemble a particular box are well within the skill of the workman in the art.

The method steps can be performed by box-assembling mechanism other than that particularly disclosed in this application, and operating elements other than that specifically disclosed can be substituted by those skilled in the art without departing from the spirit and teachings of my invention, as more particularly defined in the subjoined claims.

While certain novel features of the invention have been disclosed herein, and are pointed out in the annexed claims, it will be understood that various omissions, substitutions and changes may be made by those skilled in the art without departing from the spirit of the invention.

30. What is claimed is:

1. The method of making paperboard boxes from a relatively stiff body blank having a bottom and side wall sections and a relatively flexible wrapper blank having side wall flaps extending beyond the side edges of the side wall sections of the body blank, which includes the steps of, adhesively applying the wrapper blank to the bottom section of the body blank, thereafter applying adhesive to the side wall flaps of the wrapper blank, folding said flaps into adhesive contact with the inside face of the side wall sections while the side wall sections are substantially coplanar with the bottom sections, and bending said side wall sections at an angle to the bottom section before the adhesive applied to said side wall flaps has become set and fixed to said side wall sections.

2. The method of making paperboard boxes from a relatively stiff body blank having a bottom section and side wall sections, and a relatively flexible wrapper blank having side wall flaps extending beyond the side edges of the side wall sections of the body blank, which includes the steps of, applying a layer of adhesive to one face of the bottom section of the body blank, applying the wrapper blank to the body blank in adhesive contact with the adhesive-coated area of said bottom section, thereafter applying a strip of adhesive to the side wall flaps of said wrapper blank, folding said side wall flaps into adhesive contact with the inside face of the extended side wall sections, and bending said side wall sections at an angle to the bottom section before the adhesive applied to said side wall flaps has set.

65. 3. The method of making paperboard boxes from a relatively stiff body blank having a bottom section and side wall sections, and a relatively flexible wrapper blank having side wall flaps extending beyond the side edges of the side wall sections of the body blank, which includes the steps of, applying a layer of adhesive to one face of the bottom section only of the body blank, applying the wrapper blank in registered position over the adhesive-coated face of said body blank, applying adhesive to said side wall flaps,

folding said side wall flaps around the side edges of and into adhesive contact with the opposite face of the side wall sections of the body blank while the side wall sections are substantially coplanar with the bottom section, bending said side wall sections at an angle to the bottom section before the adhesive applied to said side wall flaps has become set and fixed to said side wall sections, and pressing said side wall flaps into firm and adhesive contact with the inside face of the side wall sections of the body blank.

4. The method of assembling a relatively flexible wrapper blank to a relatively stiff body blank in the manufacture of wrapped boxes, in which the body blank includes a bottom section and side wall sections hinged thereto, and in which the wrapper blank is provided with side wall flaps extending beyond the side edges of the side wall sections of the body blank, which includes the steps of, adhesively securing the bottom sections only of the body blank to the wrapper blank, adhesively securing the side wall flaps to the opposite face of said side wall sections of the body blank while the side wall sections are substantially coplanar with the bottom section, bending said side wall sections at an angle to the bottom section before the adhesive applied to said side wall flaps has become set and fixed to said side wall sections, and pressing said side wall flaps into firm adhesive contact with the inside face of the side wall sections of the body blank.

5. The method of making paperboard boxes from a relatively stiff body blank having a bottom section and side and end wall sections hinged thereto, and a wrapper blank provided with side and end wall flaps extending beyond the free edges of the respective side and end wall sections of the body blank, which includes the steps of, adhesively securing the bottom section only of the body blank to the wrapper blank, thereafter adhesively securing the side wall flaps to the opposite face of the side wall sections of the body blank, thereafter applying adhesive to the end wall flaps of said wrapper blank, erecting the side and end wall sections of the body blank into a position substantially at right angles to the bottom section, and folding the end wall flaps of the wrapper blank into adhesive contact with the inside face of the end wall sections of the body blank.

6. The method of making paperboard boxes from a relatively stiff body blank having a bottom section and side and end wall sections hinged thereto and a wrapper blank having side and end wall flaps extending beyond the free edges of the respective side and end wall sections of the body blank, which includes the steps of, adhesively securing the bottom section only of the body blank to the wrapper blank, adhesively securing the side wall flaps to the opposite face of the side wall sections of the body blank while the side wall sections are substantially coplanar with the bottom section, bending said side wall sections at an angle to the bottom section before the adhesive applied to said side wall flaps has become set and fixed to said side wall sections, erecting the side and end wall sections of the body blank into a position substantially at right angles to the bottom section, and folding the end wall flaps of the wrapper blank into adhesive contact with the inside face of the end wall sections of the body blank.

7. The method of making paperboard boxes from a relatively stiff body blank having a bot-

tom section, side and end wall sections, and corner tabs extending from said side wall sections, and a wrapper blank having side and end wall flaps extending beyond the free edges of

5 the respective side and end wall sections of the body blank, which includes the steps of, adhesively securing the bottom section only of the body blank to the wrapper blank, adhesively securing the side wall flaps to the opposite face

10 of the side wall sections of the body blank, folding said corner tabs into a position substantially at right angles to the side wall sections, erecting the side and end wall sections of the body blank into a position substantially at right angles to

15 the bottom section, and folding the end wall flaps of the wrapper blank into adhesive contact with the inside face of the end wall sections and the corner tabs of the body blank.

8. The method of making paperboard boxes

20 from a relatively stiff body blank having a bottom section, side and end wall sections, and corner tabs extending from said side wall sections, and a wrapper blank having side and end wall flaps extending beyond the free edges of

25 the respective side and end wall sections of the body blank, which includes the steps of, adhesively securing the bottom section only of the body blank to the wrapper blank, adhesively securing the side wall flaps to the opposite face

30 of the side wall sections of the body blank, bending said side wall sections at an angle with the bottom section before the adhesive applied to said side wall flaps has become set and fixed to said side wall sections, folding said corner tabs

35 into a position substantially at right angles to said side wall sections, erecting the side wall sections of the body blank into a position substantially at right angles to the bottom section, erecting the end wall sections of the body blank

40 substantially at right angles to the bottom section and into abutting position against said corner tabs, and folding the end wall flaps of the wrapper blank into adhesive contact with the inside face of the end wall sections and the

45 corner tabs of the body blank.

9. The method of making paperboard boxes from a relatively stiff body blank having a bottom section, side and end wall sections, and corner tabs extending from said side wall sec-

50 tions, and a wrapper blank having side and end wall flaps normally extending beyond the free edges of the respective side and end wall sections of the body blank, which includes the steps of, arranging the body blank and wrapper blank in

55 juxtaposed position, thereafter applying adhesive to said side wall flaps, folding said side wall flaps into adhesive contact with the side wall sections of the body blank, folding said corner tabs into a position substantially at right angles to said

60 side wall sections, folding said side wall sections into a position substantially at right angles to said bottom section, folding the end wall sections substantially at right angles to the bottom section, and folding the end wall flaps of the wrapper blank into adhesive contact with the inside face of the end wall sections.

10. The method of making paperboard boxes from a relatively stiff body blank having bottom, side and end wall sections, and a wrapper blank

70 having side and end wall flaps normally extending beyond the free edges of the respective side and end wall sections of the body blank, which includes the steps of, placing the wrapper blank in juxtaposition to the body blank, thereafter applying adhesive to said side wall flaps, folding

the side wall flaps of the wrapper blank into adhesive contact with the side wall sections of the body blank, applying adhesive to the end wall flaps, folding said side and end wall sections into a position substantially at right angles to the bottom section, and folding the end wall flaps of the wrapper blank into adhesive contact with the inside face of the end wall sections of the body blank.

11. Apparatus for making wrapped paper- 10 board boxes from a relatively stiff body blank having a bottom section and side wall sections and a wrapper blank having side wall flaps ex- 15 tends beyond the free edges of the side wall sections of the body blank, said apparatus in- cluding, blank-advancing mechanism, means for feeding body blanks onto said blank-advanc- 20 ing mechanism, means for applying a coating of adhesive to the bottom section of the body blank as it moves along said advancing mechanism, means for positioning wrapper blanks in regis- 25 tered position on the successive advancing body blanks, means for applying adhesive to the side wall flaps of said wrapper blank, and means for folding said side wall flaps around said side wall sections and into adhesive contact therewith.

12. Apparatus for applying a wrapper to a relatively stiff body blank including, a stationary table, means for feeding successive body blanks onto said table, means for advancing said body 30 blanks in predetermined spaced relationship along said table, means for applying adhesive to one face of the body blanks as they successively advance along said table, wrapper blank-feeding means for feeding successive wrapper blanks into 35 position upon the adhesive-coated face of the successive body blanks as they advance along said table, means for applying a strip of adhesive to a flap on said wrapper blank extending beyond the edge of the body blank, and means for wrapping 40 said flap around the edge of said body blank.

13. Apparatus for making wrapped paperboard boxes from a relatively stiff body blank having a bottom section and side wall sections and a wrap- 45 per blank having side wall flaps extending be- 50 yond the free edges of the side wall sections of the body blank, said apparatus including, blank-advancing mechanism, means for feeding a body blank into operative engagement with said blank-advancing mechanism, means for applying ad- 55hesive to the bottom section of the body blank, wrapper blank-feeding means for feeding a wrapper blank into position upon the adhesive- 60 coated face of the body blank as it is advanced by said blank-advancing mechanism, means for effecting proper registry between the body blank and the wrapper blank applied thereto, means 65 for applying a strip of adhesive to said side wall flaps, means for wrapping said flaps around the adjacent side wall sections of the body blank, 70 and means for bending said side wall sections at an angle to the bottom section before the adhesive applied to said side wall flaps has become set and fixed to said side wall sections.

14. Apparatus for applying a wrapper to a rela- 65 tively stiff body blank having a bottom section and side wall sections, the wrapper blank having side wall flaps which normally extend beyond the side wall sections of the body blank, said ap- 70 paratus including, an elongated table having a width approximately that of the bottom section of the body, means for feeding a body blank onto one end of said table with the side wall sections thereof overhanging the side edges of the table, means for advancing a body blank along said ta- 75

ble, means for applying a coat of adhesive to the bottom section of the body blank, wrapper blank-feeding means for feeding a wrapper blank into registered position upon the adhesive-coated face of the body blank as it advances along said table, 5 means for pressing the wrapper blank into adhesive contact with the adhesive-coated surface of said bottom section, means for applying a strip of adhesive to said side wall flaps, and means for wrapping said flaps around the adjacent side wall sections of the body blank.

15. Apparatus for applying a wrapper to a relatively stiff body blank, the wrapper blank having side wall flaps which normally extend beyond the side wall sections of the body blank, 10 said apparatus including, means for placing a wrapper blank in juxtaposition to said body blank with the side wall flaps overhanging the side edges of said body blank to provide a blank assembly, a blank assembly-supporting surface having a width less than the width of the wrapper blank, means for positioning said blank assembly on said supporting surface with the side wall flaps overhanging the side edges of said supporting surface, means for advancing said blank assembly forwardly along said supporting surface, 20 means for applying a strip of adhesive to one face of said side wall flaps, means for folding said side wall flaps over the adjacent side edges of said body blank as it advances along said supporting surface, and means for folding said flaps inwardly into adhesive contact with said body blank as the blank assembly advances along said supporting surface.

35. 16. Apparatus for applying a wrapper to a relatively stiff body blank, the wrapper blank having side wall flaps which normally extend beyond the side edges of the body blank, said apparatus including, means for placing a wrapper blank into 40 juxtaposition over said body blank with the side wall flaps overhanging the side edges of said body blank to provide a blank assembly, a belt conveyor having a width less than the width of the wrapper blank, means for feeding said blank assembly onto said belt conveyor with the side wall flaps overhanging the side edges of said belt conveyor, means for driving said belt conveyor, means for retaining said blank assembly upon said belt conveyor during its travel thereon, means for applying a strip of adhesive to one side face of the side wall flaps as they advance along said belt conveyor, and normally stationary means for folding said flaps inwardly into adhesive contact with said body blank as the blank assembly 50 advances along said belt conveyor.

55. 17. Apparatus for applying a wrapper to a relatively stiff body blank, the wrapper blank having side wall flaps which normally extend beyond the side edges of the body blank, said apparatus including, 60 a traveling conveyor having a blank-supporting surface of less width than said wrapper blank, means for applying adhesive to the body blank, means for applying a wrapper to the adhesive-coated surface of said body blank to provide a blank assembly, means for feeding successive blank assemblies onto the blank-supporting surface of said conveyor in predetermined spaced relationship with the side wall flaps of the wrapper blank overhanging the side edges of the blank-supporting surface of said conveyor, means for applying adhesive in strip form to the overhanging side wall flaps as they are advanced forwardly by said conveyor, pivotally mounted folding elements operative to fold said flaps over the

adjacent side edges of the advancing body blanks, means for driving said pivoted folding elements, and stationary means for turning the side wall flaps inwardly into adhesive contact with the successive advancing body blanks.

5 18. Apparatus for making wrapped paperboard boxes from a relatively stiff body blank having a bottom section and side and end wall sections and a wrapper blank having side and end wall flaps normally extending beyond the free edges 10 of the respective side and end wall sections of the body blank, said apparatus including, means for adhesively securing a wrapper blank in registered position upon said body blank, means for applying adhesive to the side wall flaps of said 15 wrapper blank, means for folding said flaps into adhesive contact with the side wall sections of said body blank providing a blank assembly, a support for said blank assembly, means for advancing said blank assembly along said support, 20 means for folding the end wall flaps over the free edges of the end wall sections of the body blank, means for applying a strip of adhesive to each of said end wall flaps as the blank assembly is advanced along said support, box-erecting mechanism, and means for feeding said blank assemblies into said box-erecting mechanism.

25 19. Apparatus for making wrapped paperboard boxes from a relatively stiff body blank having a bottom section, side and end wall sections, and 30 corner tabs extending from said side wall sections, and a wrapper blank having side and end wall flaps normally extending beyond the free edges of the respective side and end wall sections of the body blank, said apparatus including, means for adhesively securing a wrapper blank in registered position upon said body blank providing a blank assembly, means for applying adhesive to the side wall flaps of said 35 wrapper blank, means for folding the side wall flaps into adhesive contact with the side wall sections of said body blank, means for applying adhesive to the end wall flaps, box-erecting mechanism, and means for feeding the blank assembly into said box-erecting mechanism.

40 20. Apparatus for making wrapped paperboard boxes from relatively stiff body blanks each having a bottom section, side and end wall sections, and corner tabs extending from said side wall sections, and wrapper blanks each having side and end wall flaps normally extending beyond the free edges of the respective side and end wall sections of the body blanks, said apparatus including, means for advancing successive body blanks in predetermined spaced relationship, means for applying adhesive to the bottom section of the successive advancing body blanks, means for feeding successive wrapper blanks into adhesive contact with the adhesive-coated bottom section of the successive advancing body blanks, means for applying adhesive to the side wall flaps of the successive advancing wrapper blanks, means for folding the side wall flaps of the successive advancing wrapper blanks into adhesive contact with the side wall sections of the body blanks to which they are adhesively secured, means for bending the side wall sections at an angle to the bottom section of the successive advancing body blanks, means for applying adhesive to the end wall flaps of the successive advancing blanks, box-erecting mechanism, and means for feeding said blanks successively into said box-erecting mechanism.
